DUMP WAGON

Theodore C. Harvey, Philadelphia, Pa.

Original application February 8, 1933, Serial No. 655,744. Divided and this application October 14, 1933, Serial No. 693,545

5 Claims. (Cl. 298—8)

This is a divisional application of a copending application filed February 8, 1933, Serial No. 655,744.

This invention relates to dump wagons, the broad object of said invention being to provide a wagon of the class described, which is capable of various operations in order to expedite and facilitate the discharge of the load therefrom in a manner most convenient to the operator as well as minimizing traffic obstruction.

One object is to provide a dump wagon having a bottom discharge and capable of being automatically emptied or unloaded, partially or wholly from either side of the wagon body.

Another object in view, is to provide for emptying the load partially or wholly from the bottom.

Another object in view, is to provide for directing the discharging load toward either side, bottom, front and rear or practically in almost any direction downwardly or inclined from the bottom discharge opening of the load body.

Another object in view, is to provide means for the carriage of separate units or different materials and permitting separate or combined discharge of said load units.

Another object in view, is to provide means for leveling, stabilizing or distributing the load body contents after part of the load has been discharged and the remainder is carried to a different destination.

Another object in view, is to provide means for the sectional removal or assembly of the load body division boards as may be required.

With the above and other objects in view, the invention consists substantially in the combination, construction, location and relative arrangement of parts, all as will appear more fully hereinafter, as shown in the accompanying drawings and as finally pointed out in the appended claims.

In the accompanying drawings:

Figure 1 is a side elevational view of a dump wagon constructed in accordance with and embodying the principles of the present invention;

Figure 2 is a plan view of the dump wagon embodying the present invention, the fore and aft standards being shown in horizontal section;

Figure 3 is a side elevational view of the displaceable, longitudinal, center or division board and gate operating means;

Figure 4 is a top cross-sectional view of the central, grooved or channeled binding post for

engaging the central ends of the four division wall sections; and

Figure 5 is a top plan view of the dump body, division walls and division wall gate operating means.

Referring now more particularly to the drawings, it will be observed that the wagon body or receptacle for the load as shown is of inverted frusto-pyramidal shape. While this is the preferable shape, it will be understood that the invention or inventions to be described more fully hereinafter are equally applicable to bodies or load receptacles of different shapes than that shown in the drawings, the principal characteristic of the body with which this invention is concerned being that the side walls thereof converge downwardly toward an opening in the bottom of the body. In the drawings the load receiving body is designated generally by the reference numeral 10, the centrally disposed bottom opening or outlet having suitably secured to the perimetral edge thereof a frame member provided with intersecting division strips 11 and 12 whereby to provide a plurality of substantially equal-sized openings 13, each of which constitutes an individual discharge outlet. It will be apparent that by the provision of the four discharge outlets, the material contained in the body may be discharged through any one or more of the said discharge outlets.

As is described in my copending application above identified, each of the discharge outlets 13 thus provided in the bottom of the body is adapted to be opened and closed by a horizontally arranged slideable closure member, these closure members being all movable in directions extending longitudinally of the main body 10. The arrangement of these closure members and the means for effecting their operation will not be described herein. Should a more detailed description thereof be desired, reference is made therefor to my copending application Serial No. 655,744.

As appears most clearly in Figure 1, the main body 10 rests upon and is directly supported by a foundation board or platform 14 having formed therein an elongated central opening 15. This platform 14 is adapted for vertical movement together with the main body 10 supported thereby by means to be described hereinafter. The platform 14 is, of course, disposed in a substantially horizontal plane above the vehicle frame 16. The fore and aft ends of the vehicle frame side members are preferably in the

form of partially boxed-in sections the vertical side walls of which are each provided with a centrally disposed opening 17. Disposed between the openings 17 in the opposite side walls of the vehicle frame and suitably secured to the bottom end of the main body 10 is a revoluble discharge chute 20, the vehicle frame 16 being of a sufficient depth to allow for the desired vertical and rotative movement of the discharge chute 20.

The vehicle frame 16 is of substantially rectangular formation, thus permitting not only a vertical movement of the discharge chute 20 therewithin but also a circular movement thereof when the body 10 is in lowered position, the openings 17 in the side walls of the vehicle frame being of sufficient length and depth as to permit the free movement therethrough of the outer end of the discharge chute.

Suitably secured to the upper end of the circular body of the discharge chute 20 is an annular rack bar or worm gear 21 which is adapted for meshing engagement with and actuation by a worm 22 fixed to a transverse shaft 23 the opposite ends of which are journalled, as at 24a, (see Figure 2) to the foundation board or platform 14. This shaft 23 is arranged to be driven, through a system of meshed bevel gears, by a vertically extending rotatable shaft 24. This shaft 24 is suitably encased within a supporting tube or casing 25 which is securely held in position at its upper end by a bracket 26 (see Figure 2) mounted upon the side of the main body 10.

Secured to the lower end of the shaft 24 is an operating handle (not shown herein) for effecting the desired rotation of the revoluble discharge chute 20 from the ground regardless of the vertically adjusted position of the main body, the arrangement being such that regardless whether the said body is raised or lowered, the transverse shaft 23 is constantly in operative association with the vertical operating shaft 24. Preferably, the lower end of the rotatable shaft 24 is journalled within a bracket (not shown herein) mounted upon the side edge of the vehicle frame 16.

Mounted upon the upper frame member 16 of the vehicle truck at the fore and aft ends thereof are a pair of uprights or standards 27 and 28. Inasmuch as these standards and their associated parts are described in detail in my copending application aforesaid and in view also of the fact that these standards are not vitally essential to the operation of the invention with which this application is concerned, their construction will not be described herein, it being sufficient for the present purposes merely to point out that these standards 27 and 28 embody elevating means for raising and lowering the main body 10 as may be desired.

Preferably, the upper ends of the fore and aft standards 27 and 28 are preferably respectively covered by the caps 29 retained in position by means of the screw bolts 30. These standards 27 and 28 are respectively slotted, as at 31, in the faces thereof which present toward each other in order to permit the free vertical movement of the substantially T-shaped extensions 32 provided at either end of the foundation board or platform 14, these extensions being retained within the standards 27 and 28 and guided during the vertical movement of the platform by the vertically extending ribs 33 which define the vertically extending slots 31

in the standards. Preferably, the standards are each strengthened and supported by side braces or ribs 34 (see Figures 1 and 2).

The mechanism for operating the bottom trap doors for controlling the discharge outlets 13 will not be described herein, said mechanism being described in my copending application aforesaid, it being deemed sufficient merely to point out that these trap doors are adapted to be selectively operated by the hand wheels 35, 10 36, 37 and 38, similar sets of the latter being provided upon either side of the vehicle. As an alternating means for operating the trap doors, there may be provided the pull cords, 39, 40, 41 and 42; or the hand-operated levers 43, 44, 45 15 and 46.

As appears most clearly in Figure 1, the main body 10 is provided with a plurality of side loading doors 47, these doors being respectively adapted for movement in vertical planes, the 20 doors being closed when they are moved into their uppermost position as shown in Figure 1. Preferably, a pair of such doors are arranged to either side of the main body in longitudinally spaced relation.

The mechanism for operating these side loading doors 47 will be but briefly referred to herein, it being deemed sufficient for the purpose of this divisional application to point out that the side loading doors are arranged for simultaneous operation by means of vertically arranged elevating screws 48, all of the latter being commonly actuated by a shaft 49 to which desired rotation is imparted by a forwardly located hand operated wheel 50.

It is preferable to provide some means for subdividing the main body 10 into a plurality of individual compartments and to this end there is provided a pair of vertical sections 51 and 52 and a second pair of vertical sections 53 and 54, 40 these vertical sections being so formed along their inner vertical edges as to permit their slideable retention within suitably formed vertically extending slots, grooves or channels 55 provided in a central vertical post 56 (see more particularly Figure 4), this central vertical post 56 serving to detachably secure the division wall sections 51 to 54 together. Suitable bifurcated lugs 57 or the like are secured to the inner faces of the side walls of the main body 10 for respectively receiving the outer edges of the division wall sections 51 to 54, these lugs 57 being preferably provided with set screws 58 or the like for rigidly securing and retaining the division wall sections in position. As appears quite 55 clearly in Figure 2, the division wall sections when properly positioned within the main body 10 constitute in effect a longitudinally extending partition which is intersected substantially at right angles by a transversely extending partition, the longitudinally extending partition being disposed substantially in the plane of the division strip 12 of the bottom frame and the transversely extending partition being disposed substantially in the plane of the transversely 60 extending division strip 11 of the bottom frame. There is thus provided four compartments which are respectively provided with the discharge openings 13 (see Figure 2), each of which openings is provided with its own individually operated trap door, as already described. The four compartments so provided are thus adapted to be filled with different materials for individual or selective discharge through their respective discharge openings or the four compartments 75

may be filled with material adapted to be discharged in one operation by simultaneously opening all of the trap doors. Preferably, the upper edges of the division strips 11 and 12 of the frame surrounding the bottom opening in the main body 10 are grooved or slotted longitudinally thereof to snugly accommodate the bottom edges of the division wall sections 51 to 54.

As appears most clearly in Figure 3, each of the division wall sections 51 to 54 is provided in the bottom thereof with a vertically movable gate 59. Each of these gates 59 has fixed adjacent the upper edge thereof an interiorly threaded socket 60 or the like through which is vertically projected a vertically extending screw 61, this screw being suitably journalled in a bearing 62 secured to the upper portion of the division wall section. Fixed to the upper end of each screw 61 is a pinion or gear wheel 63, the pinions 63 so carried by the vertical screws of the transverse division wall sections 52 and 54 respectively engaging suitable worm gears or the like 64 carried by short shafts 65 and 66. These shafts 65 and 66 extend in opposite directions from the central axis of the main body 10 and are journalled for rotation in suitable bearings 67 mounted upon the upper edges of the transverse division wall sections 52 and 54. As appears most clearly in Figure 5, the proximate ends of the shafts 65-66 are respectively provided with pinions or gear wheels 68 and 69.

Extending longitudinally of the main body 10 and lying substantially in the plane of the division wall sections 51 and 53 is a shaft 70, this shaft being provided with a screw or worm gear 71 for meshing engagement with the pinion 63 of the screw 61 carried by the forward division wall section 51. The forward portion of the longitudinally extending shaft 70 is supported within a split bearing mounted upon the upper edge of the forward division wall 51, one portion of this bearing being hinged to the other portion thereof whereby the bearing may be opened to permit the removal of the shaft. The split bearing is preferably maintained closed by means of a thumb screw 72 or the like. The longitudinally extending shaft 70 is projected through a second tubular shaft the forward end of which is provided with a bevel gear or pinion 73 adapted for meshing engagement with the bevel gear or pinion 69 carried by the short transversely extending shaft 66. This second tubular shaft is in turn projected through a third tubular shaft 74, the forward end of which is also provided with a bevel gear or pinion 75 adapted for meshing engagement with the bevel gear or pinion 68 carried by the other transversely extending shaft 65. The last-mentioned tubular shaft 74 is projected through still another tubular shaft 76, the latter being provided at a somewhat removed distance from its forward end with a worm or other such gear 77 which is adapted for meshing engagement with the bevel gear or pinion 63 fixed to the upper end of that vertically extending screw 61 which is carried by the rearward division wall section 53.

It will thus be observed that the central shaft 70 and the three tubular shafts embracing the same are all coaxially arranged with respect to each other, the outermost shaft being of shortest length and the innermost central shaft being of greatest length. This coaxial shaft assembly is suitably supported or journalled within bearings 78-79 in longitudinally spaced relation upon

the upper edge of the rearward division wall section 53. Preferably, the central shaft 70 and the tubular shafts surrounding the same are separated from each other by suitable ball or roller bearings (not shown).

Respectively secured to the rear ends of these four coaxially arranged shafts are the hand wheels 79, 80, 81 and 82, it being apparent that upon rotation of the hand wheel 79, the gate in the rearward division wall section 53 may be lifted vertically. Similarly, by operating the hand wheel 81 the gate in the division wall section 54 may be vertically raised or lowered, while operation of the hand wheels 80 and 82 respectively effect vertical movement of the gates in the division wall sections 52 and 51.

Preferably, the division wall sections each are provided with hand holes 83 (see Figure 3) to permit the removal of these sections by means of an overhead crane or tackle. By means of the selectively movable gates 59 in the several division wall sections 51 to 54, the operator of the vehicle may readily stabilize the load contained in the main body 10 after a part of this load has been delivered or he may speed up the discharge of the load, as when only one of the four compartments is filled with a slow-moving material and it is desired to make available all four of the bottom discharge outlets 13, it being obvious in such case that when all of the gates are raised the discharge of the material from the single-filled compartment will be greatly accelerated.

These division wall sections which sub-divide the main body into a plurality of separate and independent compartments allow for single or multiple delivery at the same time that they provide a very effective means for stabilization of a part load in order to afford safer transit over rough roads. The vertically movable gates in these division wall sections facilitate not only this stabilization of the load but also may be employed for accelerating the discharge of a slowly moving material.

It will be understood, of course, that the invention is susceptible of various changes and modifications which may be made from time to time without departing from the real spirit or general principles thereof and it is accordingly intended to claim the same broadly, as well as specifically, as indicated in the appended claims.

What is claimed as new and useful is:—

1. A dump wagon of the character described comprising, in combination, a main body constituting the load receptacle and being provided in the bottom thereof with a discharge opening, a vertically extending post within said main body, said post being provided with a plurality of circumferentially spaced vertically extending grooves, and a plurality of removable partition members arranged within said main body with the inner vertical edges of said partition members respectively slidably received within said grooves of said post, said partition members being relatively so arranged with respect to each other and with respect to said main body as to provide the latter with a plurality of independent compartments having discharge openings which respectively constitute portions of the bottom opening in said main body.

2. A dump wagon of the character described comprising, in combination, a main load receiving body having a discharge opening in the bottom thereof, a plurality of independently removable individual partitions arranged within said

- main body in intersecting relation whereby to provide said body with a plurality of independent compartments, and a vertically slidable gate in each of said partitions for effecting communication between any two adjacent compartments or between all of said compartments.
3. A dump wagon of the character described comprising, in combination, a main load receiving body having a bottom discharge outlet, a plurality of partition members removably arranged within said main body to divide the latter into a plurality of independent compartments the interiors of which are in communication with said bottom discharge opening of the main body, means for slidably receiving the inner vertical edges of said partition members to maintain them in intersecting relation, a vertically movable gate provided in each of said partitions, and gear-operated screw means operatively associated with each gate for lowering or raising the same for the purpose specified.
4. A dump wagon of the character described comprising, in combination, a main load receiving body having a bottom discharge outlet, a plurality of independent partition members removably arranged within said main body to divide the latter into a plurality of independent compartments the interiors of which are in communication with said bottom discharge opening of the main body, said partition members being individually removable from said main body, a vertically movable gate provided

in each of said partitions, and gear-operated screw means operatively associated with each gate for lowering or raising the same for the purpose specified, said gear-operated screw means being selectively operable to raise or lower any one of said gates independently of the others thereof.

5. A dump wagon of the character described comprising, in combination, a main load-receiving body having a bottom discharge opening, a plurality of removable partition members arranged within said body in intersecting relation whereby to provide said body with a plurality of independent compartments, a vertically movable gate arranged in each of said partition members, a screw carried by each partition member and operatively associated with each gate for effecting the raising or lowering movement of the latter, a plurality of telescopically arranged shaft members extending longitudinally of said main body with the outer ends thereof arranged exteriorly of said main body, each of said shafts being geared to one of said screws, and means at the outer extremities of said telescopic shafts for selectively or collectively operating the same whereby to effect the vertical movement of any one or more of said gates.

THEODORE C. HARVEY. 30
